(57) **CLAIM**

The ornamental design for a pet food bowl, as shown and described.

DESCRIPTION

FIG. 1 is a front and top perspective view of a pet food bowl in accordance with my new design;
 FIG. 2 is a top plan view thereof;
 FIG. 3 is a bottom plan view thereof;
 FIG. 4 is a left side elevational view thereof;
 FIG. 5 is a right side elevational view thereof;
 FIG. 6 is a rear elevational view thereof; and,
 FIG. 7 is a front elevational view thereof.
